UNITED STATES PATENT OFFICE.

ROBERT N. ALLEN, OF METHUEN, MASSACHUSETTS, ASSIGNOR TO U. S. BOBBIN & SHUTTLE COMPANY, OF PROVIDENCE, RHODE ISLAND, A CORPORATION OF NEW JERSEY.

BOBBIN-CLAMP FOR SHUTTLES.

1,145,650.

Specification of Letters Patent. Patented July 6, 1915.

Application filed December 17, 1914. Serial No. 877,630.

To all whom it may concern:

Be it known that I, ROBERT N. ALLEN, a citizen of the United States, residing at Methuen, in the county of Essex and State 5 of Massachusetts, have invented a new and useful Improvement in Bobbin-Clamps for Shuttles, of which the following is a specification.

This invention relates to certain new and 10 useful improvements in bobbin clamps for shuttles, and the primary object thereof is to provide a novel and improved form of clamp in which the guide member is formed to have arms which engage and secure the 15 spring arms which grip the bobbin.

A further object of the invention is to provide a clamp in which the guide member and spring arms are secured to one another without the use of extraneous fastening 20 means, thus economizing in production of the structure and in assembling of the parts.

Other and further objects of the invention will be later set forth and evidenced in 25 the course of the following description.

In the drawings—Figure 1 is a top plan view of the invention, the shuttle being broken partly away and shown in section. Fig. 2 is a vertical longitudinal sectional 30 view of Fig. 1. Fig. 3 is a section on the line 3—3 of Fig. 2. Fig. 4 is a plan view of the blank from which the guide is formed, and Fig. 5 is a similar view of one of the blanks from which the spring jaws 35 are formed.

In proceeding in accordance with the present invention, a guide member is formed from a blank of the form shown in Fig. 4 to have parallel top and bottom parts 1 and 40 2 and a guide proper 3 which is inclined and connects the parts 1 and 2. The parts 1 and 2 are formed with openings 4 which register in the manner illustrated in Fig. 2 of the drawings. The base or bottom part 2 is 45 formed with a widened foreportion 5 for a purpose now to be described. The spring jaws 6 are formed of separate pieces and have shanks 7 which latter are in contacting relation and are received in the space between the top and bottom parts 1 and 2 of the 50 guide member. The top and bottom edges of the shanks of the jaws are formed with outwardly projecting lugs 8 which are received in the openings 4—4 of the top and bottom parts 1 and 2, as depicted more

clearly in Fig. 2 of the drawings. The shanks 7 also have registering apertures 9 through which a securing bolt 10 passes for the purpose of securing the entire structure to the shuttle.

It will be apparent from the foregoing that the guide member thus acts as a means of securing the jaws in position and to itself without the use of extraneous fastening means, since the lugs 8 are formed integral 60 with the shanks of the jaws and are received in openings provided therefor in the top and bottom parts of the guide member.

The inclined guide proper 3 also has its opposite sides engaged by the bent portions X of the spring jaws, as shown in Figs. 1 and 2 of the drawings, thus preventing accidental or other lateral movement of the two parts relatively to each other, since the bent portions X of the jaws embrace the 70 guide proper 3, and extend on opposite sides thereof.

The lugs preferably have sufficient play within the openings 4 in order to enable leverage action of the spring arms so that 80 same will fulcrum on the lugs. The lugs 8 by virtue of engaging in the openings 4 prevent the jaw shanks from relative spreading.

The widened base parts 5 provide seats 85 which afford firm and effective bearings or supports for the lower edges of the shanks 7 and the curved parts X thereof, as shown in Fig. 1.

Having thus described my invention, I 90 claim as new and desire to secure by Letters Patent;—

1. In a bobbin clamp for shuttles, a guide member having a top and a bottom part each having a single opening, which two 95 openings register, and a pair of jaws having abutting shanks each provided with an upwardly and a downwardly extending lug, the two lugs at the bottoms of the shanks being jointly received in the single opening of the bottom part, and the two lugs at the tops of the shanks being jointly received in the single opening of the top part.

2. In a bobbin clamp for shuttles, a guide member consisting of connected top and bottom parts, each having an aperture formed therein, a pair of jaws having shanks the top and bottom edges of which are engaged with the under and upper faces respectively of said top and bottom parts, 100 105 110

and a lug formed upon the top and bottom edge of each shank, the adjacent lugs being arranged with their inner faces in contacting relation and jointly received in the respective apertures of the top and bottom parts.

In testimony whereof I have signed my

name to this specification in the presence of two subscribing witnesses.

ROBERT N. ALLEN.
